CLAIM

The ornamental design for a support for arm, hand and wrist, as shown and described.

DESCRIPTION

FIG. 1 is a top perspective view of a support arm, hand, and wrists showing my new design;

FIG. 2 is a top plan view thereof;

FIG. 3 is a front elevational view thereof;

FIG. 4 is a rear elevational view thereof; and,

FIG. 5 is a side elevational view thereof the opposite side is a mirror image.

The broken line showing of the microscope and table in FIG. 1 is for illustrative purposes only and forms no part of the claimed design.
